UNITED STATES PATENT OFFICE.

GUY D. FRENCH, OF DINSDALE, IOWA.

TRAVELING CONVEYER.

1,247,388.

Specification of Letters Patent. Patented Nov. 26, 1917.

Application filed August 26, 1916. Serial No. 116,642.

To all whom it may concern:

Be it known that I, GUY D. FRENCH, a citizen of the United States, and resident of Dinsdale, in the county of Tama and State of Iowa, have invented certain new and useful Improvements in Traveling Conveyers, of which the following is a specification.

The present invention relates to the class of loading and unloading and has particular reference to new and useful improvements in traveling conveyers.

The primary object of my invention is to provide a traveling conveyer for use in removing material in bulk from a lower level and depositing the same on a higher level.

Another object of my invention is to provide a conveyer of the class described which may be folded to occupy a minimum amount of space when not in use.

20 A further object of my invention is to provide a conveyer of the class described having a strong and durable construction, cheaply manufactured, easily and quickly installed and effective in operation.

25 Other objects and advantages to be derived from the use of my improved traveling conveyer will appear from the following detail description and the claims, taken with an inspection of the accompanying drawings, in which:

Figure 1 is an end elevational view of a receiving building and a railway car showing my improved conveyer in side elevation;

Fig. 2 is a top plan view of the same;

Fig. 3 is an enlarged perspective view of the carrier frame detached;

Fig. 4 is an enlarged fragmentary sectional view of one of the trackways;

Fig. 5 is an enlarged plan view of the carriage arranged on the free end of the conveyer; and

Fig. 6 is an enlarged fragmental perspective view of a portion of the conveyer belt.

Referring more particularly to the drawings, wherein similar characters of reference designate like and corresponding parts throughout the various views, 1 designates a building for storage purposes, the building having a gable roof 2 having the usual ridge 3 and eaves 4. The roof 2 is provided with a plurality of openings 5 closed by hinged doors 6, said openings being arranged above storage bins or the like (not shown).

The device of my invention includes a carrier frame T composed of side bars 7 and 8 having the inner ends thereof laterally

bent to provide arms 9 and 10, said arms being offset at 11 to provide tongue portions 12, said tongue portions having bearing rollers 13 mounted thereon in spaced relation. 60 The tongue portions 12 are receivable within a tubular trackway 14, a longitudinal slot 15 being formed in said tube to accommodate said tongues. Divergent arms 16 are formed on the tubular trackway 14, said arms 16 serving to engage with the ridge 3 of the roof to retain the trackway in position thereon. The bars 7 and 8 are connected by transversely extending bars 17 and 18 to form a rectangular frame. 70

A pair of supporting legs 19 and 20 are hingedly connected at 21 with the arms 7 and 8, respectively, the lower free ends of the arms 19 and 20 carrying rollers 22 and 23, said rollers being adapted to run on an angle-iron trackway 24 arranged longitudinally of the roof parallel to the trackway 14 and adjacent the eaves 4. A pair of brace arms 25 and 26 connected at their upper free ends to the arms 9 and 10 as indicated at 28, said connections being adjustable by virtue of a plurality of openings 29 provided in said braces. 85

The conveyer proper is composed of two sections S and S', said sections being composed of side frames 31, 32, 33 and 34, respectively. The pairs of side bars 31 and 32 and 33 and 34 are connected by transversely extending rods 36 and 37. The upper free end of the section S is strengthened by means of a transversely extending bar 38. The section S is hinged to the frame F between the arms 9 and 10 as at 35, the arms being enlarged at 35' for this purpose. The sections S and S' are hingedly connected as at 39, the hinge being located on the under side of the side bars 31, 32, 33 and 34 to permit the conveyer structure to be "broken" 100 upwardly for removal out of operative position. A pair of hoisting cables 40 and 41 are connected at 42 to the side bars 31 and 32 of the frame S, the free ends of the hoisting cables being wound upon a cleat 44 arranged on the side wall of the house 1. I do not limit myself to this manner of hoisting the conveyer when not in use since the cables may be run in any desired manner. 105

A plurality of guide plates 45 and 46 are arranged on the bottom edges of the sections S and S' to prevent contact of the same with

the roof or with a freight car or the like when in use and to prevent the conveyer belt from sagging.

The conveyer structure is composed of a flexible body or belt 48 having a plurality of transverse ribs 49 arranged thereon, said ribs being secured to said belt by means of a plurality of bolts 50, best shown in Fig. 6. The belt 48 is trained over rollers 51 and 52 arranged at opposite ends of the frames S and S'. The rollers 51 and 52 are mounted on shafts 53 and 54 journaled in the side bars 31, 32, 33 and 34.

The shaft 53 is extended beyond the side bars 31 and is provided with a pulley 54' over which a belt 55 is trained. A shaft 56 is journaled adjacent the free ends of the frame section S and carries pulleys 57 and 58, the belt 55 being trained over the pulley 57, and a power delivering belt 59 being trained over the pulley 58. The top flight of the conveyer is adapted to rest upon the rollers 36 and the bottom flight is adapted to rest upon the guards 45 and 46.

The section S' carries bearing blocks 60, said blocks being adjustable in slots 61, formed in the side bars 33 and 34, a pair of screws 63 serving to adjust the blocks within the slots so as to increase or decrease the tension of the belt. A hopper 64 is arranged above the lower free end of the belt into which the objects to be conveyed are deposited.

In the present instance the conveyer of my invention has been illustrated as emptying a freight car 65. I provide a carriage 66 having rollers 67, said carriage being revolvably mounted on the bottom of the conveyer by means of a pin 68. A stationary circular rack 69 is carried by the conveyer, and a lever 70 is carried by the carriage 66, said lever having a catch 71 for engagement with said circular rack. The purpose of the carriage is to facilitate movement of the car without entirely removing the conveyer therefrom, so that as a car is emptied the train may be moved relative the conveyer to permit emptying of the entire contents of the car.

The use of my improved conveyer will be apparent from the foregoing description and the accompanying drawings, and it will be readily understood that when the bin located beneath a given one of the openings has been filled the conveyer may be moved along the trackways 14 and 24 to fill the remaining bins. I do not limit myself to the manner of delivering power to the conveyer as shown, since any desired means may be employed. I desire to lay particular stress upon the novel arrangement of the section of the conveyer whereby the same may be folded out of operative position to occupy

a minimum amount of space when not in use, this being accomplished by the hoisting cables 40 and 41. A hook member 72 may be mounted on the lower free end of the conveyer section S' for engagement in an eye 73 mounted on the side wall of the house. My improved conveyer may be cheaply and conveniently installed for operation, no structural alteration of the building to which the same is applied being necessary.

From the above description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus fully described my invention, what I claim as new and desire to secure by Letters Patent, is:—

1. In a conveyer, the combination with a receiving body having a gable roof with trackways on the ridge and eaves thereof, of a carrier frame comprising side bars with bent extremities at one end, rollers carried by said extremities for engagement with the ridge track, supporting legs hingedly connected with the other end of said bars, rollers carried by said legs for engagement with the eaves track, brace arms adjustably connecting the bent extremities of the side bars and the legs, a foldable sectional endless conveyer having its upper section pivotally mounted between the extremities of the side bars of the frame, and hoisting means carried by the side bars of said frame for lifting the conveyer to folded position.

2. In a conveyer, the combination with a receiving body having a gable roof with trackways on the ridge and eaves thereof, said ridge track being tubular with a longitudinally extending slot therein, of a carrier frame comprising side bars with bent extremities at one end, said extremities being offset and extending through the slot in the ridge track, a pair of longitudinally spaced rollers on said offset portions engaging opposite sides of the adjacent edge of said track, supporting legs on the other end of the side bar carrying rollers adapted to engage the eaves track, a connection between said legs and bent extremities of the side bars, a foldable sectional conveyer carried by said frame, and hoisting means on the frame for lifting the conveyer to folded position.

In testimony whereof, I affix my signature hereto.

GUY D. FRENCH.
